PROCESS FOR DEWAXING OILS

Allan Berne-Allen, Jr., Great Kills, N. Y., assignor to Standard Oil Development Company, a corporation of Delaware

Application October 19, 1932, Serial No. 638,490

3 Claims. (Cl. 196—17)

This invention relates to the production of low cold test hydrocarbon oils, especially those derived from petroleum.

I have found that in certain types of oils, particularly those oils which have been subjected to treatment with hydrogen at high temperatures and pressures, the total wax content is frequently not distributed uniformly throughout the entire lubricating oil range, but that the wax may be concentrated to a greater or less extent in certain portions of the oil, particularly in the heavier portions. I have also found that it is possible to separate from these oils the particular fraction containing the major proportion of the wax, and that the removal of the wax from this fraction when isolated from the remainder of the oil is much less troublesome.

The present invention is particularly concerned with an improved method for producing low cold test oils from such stocks. The improvement comprises separating the lubricating oil stock from which the low cold test oil is to be produced into a lighter fraction and a heavier fraction and then subjecting only the heavier fraction, which will contain most of the wax, to dewaxing. The dewaxed heavier fraction may then be blended back with the undewaxed lighter fraction preliminarily removed. In this way I have found that the dewaxing of the heavier fraction of the oil may be effected more easily and completely so that even when blending this dewaxed portion with the undewaxed portion of the oil it is possible to obtain a final product which has a satisfactory pour point and cloud point.

It should be understood that this method is distinguished from certain other methods of dewaxing in which the total wax content of the oil is concentrated more or less in one fraction before dewaxing, by the fact that in this method a definite portion of the wax-containing oil itself is first removed and only the remaining fractions are dewaxed.

The method of carrying out my improved method will be fully understood from the following description read with reference to the accompanying drawing which is a diagrammatic view in sectional elevation of a type of apparatus suitable for my purposes.

Referring to the drawing, numeral 1 designates a supply tank for the oil to be dewaxed. The oil, especially if it is a hydrogenated distillate, should be topped first to the flash point desired in the finished product. Pump 2 draws oil from tank 1 through line 3 and forces it through line 4 into

a still 5 wherein the oil may be subjected to distillation under vacuum. The lighter fractions of the oil pass out of still 5 through line 6 and cooler 7 and are collected in tank 8. It will be understood that other methods of separating the oil into a lighter and heavier fraction may be used with equally good results.

The heavier fractions of the oil are withdrawn from the still through line 9 and are passed into a drum 10 which is fitted with a suitable agitating means such as the stirrer 11. Drum 10 is disposed within a container 12 which is adapted to be filled with a refrigerating medium such as chilled brine or other cold liquid.

A suitable diluent for use in dewaxing is stored in tank 13. This diluent may comprise a naphtha, a liquefied normally gaseous hydrocarbon such as liquid ethane, propane or butane or any other suitable solvent that may be used in dewaxing. The diluent is introduced through line 14 into drum 10 wherein it is thoroughly mixed with the oil to be dewaxed. During the mixing of the oil and diluent the temperature of the brine bath surrounding drum 10 is maintained at a temperature well above the wax separation point of the oil, say for example around 100 to 150° F. When the oil and diluent are thoroughly mixed the temperature of the brine bath in container 12 is lowered to below the wax separation point of the oil whereupon wax is caused to precipitate. The thoroughly chilled flux is withdrawn from drum 10 through line 15 and passed to a settling drum 16 which is disposed within a container 17 filled with a refrigerating medium such as chilled brine or other cold

medium. The precipitated wax is allowed to settle out in drum 16 and when completely settled the supernatant flux may be withdrawn therefrom through line 18 by pump 19 and passed through line 20 into tank 21. The dewaxed flux is withdrawn from tank 21 through line 22 by pump 23 and flows through line 24 into a still 25 wherein the diluent is removed from the oil by distillation. Vapors of the diluent pass out of the still through line 26, are cooled in cooler 27 and the condensed diluent is then returned to diluent supply tank 13 through line 28. The dewaxed oil, free from diluent, is withdrawn from the still through line 29 and collected in tank 30. The wax sludge which settles out in drum 16 may be removed therefrom through lines 31 and 32 or it may first be washed with diluent in order to extract as much of the oil contained therein as possible. Diluent for washing purposes is supplied from tank 13 through line 33

to auxiliary supply tank 34 from which the diluent may be introduced into drum 16 through lines 35, 36 and 31. The supernatant wash liquor may be withdrawn through line 18 and the oil may be recovered therefrom by distillation. This washing may be repeated one or more times. The final washed wax sludge is then withdrawn from drum 16 through line 31 and passed through lines 36 and 37 into a filter supply tank 38 from which it is withdrawn through line 39 and introduced into a filter press 40. The settling, washing and filtering equipment may be disposed within an insulated cabinet 41 which is adapted to be maintained at a suitably low temperature.

Following the dewaxing of the heavy fraction of the oil, the dewaxed oil from tank 30 by means of line 30' and the undewaxed oil from tank 8 by means of line 8' may be conducted to a blending tank 42 and may be blended to produce a finished oil of low pour point and cloud point.

In the operation of my process it will be understood that any method of dewaxing may be employed, and that although in the drawing the cold settling method has been illustrated, the process is not limited thereto. Other methods such as centrifuging and filtering may be used. Also, it should be understood that the method of dewaxing is not restricted to any particular type of diluent. The essential feature of the invention is the preliminary separation from the oil of the lighter wax-bearing fractions, the presence of which during the dewaxing I have found complicates the removal of wax from the heavier portions of the oil.

It will be understood that the oil may be initially separated into two fractions of such width that the dewaxed heavy oil when blended back with the undewaxed light oil will produce a blended oil of a predetermined pour point and cloud point. In general, oils of satisfactory pour point may be obtained by removing from 50 to 75 or 85% of the lighter portions of the oil and then dewaxing only the remaining heavier fractions. It is not essential to blend back the dewaxed heavy fractions with the lighter fractions first removed therefrom, for in some cases it may be advantageous to blend back the dewaxed fractions with light fractions obtained from some other type of oil.

The following example illustrates the application of my improved method of dewaxing:

A lubricating oil distillate obtained from Colombian crude is subjected to restricted destructive hydrogenation and a hydrogenated lubricating distillate of improved quality is obtained from the product. This hydrogenated distillate is reduced to 50% bottoms and an oil corresponding to a light motor oil is obtained. This 50% bottoms oil has the following characteristics:

Gravity, A. P. I.	26.7°
Flash	420° F.
Saybolt viscosity @ 100° F.	336 seconds
Saybolt viscosity @ 210° F.	54 seconds
Pour point	20° F.
Cloud point	36° F.

When this oil is dewaxed the pour point is reduced to 0° F. and the cloud point to below 0° F.

When however the lightest 70% of this oil is first removed by vacuum distillation and only the remaining 30% residual is dewaxed, and the dewaxed 30% is blended back with the undewaxed 70%, the blend has a pour point of 0° F. and a cloud point of 8° F. It will be observed that by dewaxing only the heaviest 30% of the oil and then blending this back with the remaining undewaxed 70%, the final oil has substantially the same pour point and cloud point as is obtained when the entire oil is dewaxed. The 30% residual may be dewaxed more easily than the entire lubricating oil fraction, and the cost of processing is reduced in proportion to the percentage of the total lubricating stock dewaxed.

In a similar experiment the heaviest 50% of the oil is dewaxed and then blended back with the remaining 50% of undewaxed oil and the blend is found to have a pour point of 0° F. and a cloud point of below 0° F.

It is thus possible to dewax only a small proportion of a heavy oil and to blend this back with a very large proportion of undewaxed oil and still obtain an oil of suitably low cloud point and pour point. Such a method not only increases the capacity of the dewaxing equipment but also facilitates the dewaxing of that portion of the oil which is actually dewaxed.

This invention is not limited by any theories of the mechanism of dewaxing nor by any details or data which have been given merely for purposes of illustration but is limited only in and by the following claims in which I wish to claim all novelty inherent in the process.

I claim:

1. An improved process for producing oils of low cold test from waxy hydrocarbon distillates of the type in which the major proportion of the wax is found in the heavier fractions which comprises separating the distillate into a lighter fraction of relatively low wax content and a heavier fraction, removing a substantial portion of the wax from the heavier fraction, and then blending the undewaxed lighter fraction with the dewaxed heavier fraction.

2. An improved process for producing lubricating oils of low cold test from waxy distillates derived from petroleum of the type in which the major proportion of the wax is found in the heavier fractions which comprises separating the distillate into two fractions, one containing a minor proportion of the wax content of the oil and the other containing a major proportion of the wax content of the oil, removing a substantial proportion of the wax from the latter fraction, and then blending the undewaxed fraction with the dewaxed fraction.

3. An improved process for producing a low cold test lubricating oil from an oil prepared by the destructive hydrogenation of a heavy petroleum fraction which comprises removing the non-viscous portions of the distillate, separating the topped hydrogenated oil into a lighter fraction and a heavier fraction, removing a substantial portion of the wax from the heavier fraction and then blending the undewaxed lighter fraction with the dewaxed heavier fraction.
